UNITED STATES PATENT OFFICE.

ROBERT C. STUBBS, OF DALLAS, TEXAS.

APPARATUS FOR MIXING CONCRETE UNDER PRESSURE.

Application filed January 23, 1923. Serial No. 614,888.

To all whom it may concern:

Be it known that I, ROBERT C. STUBBS, a citizen of the United States, residing at Dallas, in the county of Dallas and State 5 of Texas, have invented certain new and useful Improvements in Apparatus for Mixing Concrete Under Pressure, of which the following is a specification.

My invention relates to concrete mixers 10 and more particularly to apparatus for mixing concrete under pressure; and the object is to provide means for mixing concrete under pressure sufficient to overcome gravity and the advantage is that the quality of the concrete is generally improved and the process 15 of mixing concrete is simplified and made less expensive and the ingredients are more thoroughly mixed and the binder elements are made to cling on all the surfaces 20 of the large aggregate and so leave less space for surplus moisture and air. Another advantage is that provision is made for accurately determining the amount of water necessary and admitted to the other ingredients, and for measuring accurately the volume 25 of mixed concrete in each batch. Other objects and advantages will be fully explained in the following description and the invention will be more particularly pointed 30 out in the claims.

Reference is had to the accompanying drawings which form a part of this application.

Fig. 1 is a longitudinal section of the 35 drum used in the process, showing the interior mechanism. Fig. 2 is a cross-section of the drum, showing an end view of the spiral agitators or vanes. Fig. 3 is a broken sectional view, showing the construction of 40 the spirals or vanes. Fig. 4 is a detail view, illustrating the means for causing vibrations in the helical vanes.

Similar characters of reference are used 45 to indicate the same parts throughout the several views.

For the purpose of carrying out the mixing of concrete according to this invention, a drum, preferably cylindrical, is employed and this drum 1 is stationarily mounted and 50 is provided with a receiving opening 2 and a discharge opening 3. A small hopper 4 may be used for feeding material to the drum and a discharge chute 5, is provided at the discharge end of the drum 1. A slide- 55 able door or gate 6 is slidably connected to

the end of the drum for closing the discharge opening 3 during compression and mixing. The door 6 may be held closed by the pressure of the material on the door. The door slides in ways 7 at the upper end 60 of chute 5. The opening 2 is closed during a compression and mixing period. A sliding cover 8 moves through the side of the hopper 4 and in ways 9 for closing the opening 2. 65

A helical or spiral form of vanes or agitators is employed. An outer vane 10 and an inner vane 11 are employed. The vanes are preferably rectangular in cross-section, as shown in Fig. 3, and are preferably made 70 of spring metal. The object of the two vanes is to move the material in the drum in opposite directions. The outer vane is slightly inclined inwardly and the inner vane 11 is slightly inclined outwardly, reference being had to rectangular cross-sectional structure, the vanes being of appreciable width. The outer vane throws the material inwardly and towards the discharge end of the drum in operation and the 75 inner vane 11 throws the material outwardly and back towards the closed or receiving end of the drum. Both vanes are fixedly connected with a driving shaft 12 and are driven by this shaft in the same direction. 80 The outer vane may be left hand and the inner vane right hand and vice versa, but both should not be the same. A gear wheel 13 is rigid with shaft 12 and meshes with a pinion 14 which is driven by a motor 15. 85 The construction and arrangement of the vanes cause the material to be thrown in opposite directions. The pinion 14 should be of sufficient width to permit axial movement of the shaft 12 and wheel 13 so that the 90 outer vane 10 may be made to revolve close to the end of the drum. The vanes may be provided with metal plates 21 to aid in the agitation of the material. 95

In order to prevent any vacancy or air 100 pockets in the drum during operation, a plunger or compressor 16 is employed and more or less force or power may be applied to the compressor 16 to secure the necessary pressure to force the compressor with- 105 in the material in the drum to expand the material throughout the interior of the drum. Sufficient pressure to overcome gravity in the mixture should be employed. The power applied may be furnished by a spring 110

17 which may bear against the end of the compressor, or a lever 18 may be used. The spring 17 may be attached to the end of the drum. The lever 18 may be provided with 5 a fulcrum 19 which is mounted on the drum. It is apparent that other means may be used to force the compressor 16 into the drum. The drum may be withdrawn by a cable 10. When a quantity of material has 10 been sufficiently mixed the door 6 will be opened and the material will be forced out of the drum by pressure while the vanes are being rotated. The principal function of the vanes and the compressor is to mix the 15 material or component parts of the concrete under pressure. Herein lies a great difference between this improved mixer and the previous mixers. The previous mixers distribute the aggregate but do not force the 20 binder particles onto the surface of the larger aggregate with friction caused by pressure on the mass. The usual mixing is done in a loose state of the mass. With the improved mixer, the mixing is done in a 25 compacted state of the mass. In the usual mixing the discharge must wait until the drum has revolved enough to empty the batch finally. In the improved apparatus, the discharge is forced under pressure at the 30 rate desired. Friction between the particles is required to establish their closest relation and the resulting benefit of the mixing will depend upon the amount of friction applied. Power is required in securing a mixture of the particles with greatest binding 35 relation and unless considerable power is consumed or applied, little friction will occur between the particles to be bound. The prime object of my invention is to secure 40 positive contact and final maximum bond between particles of a mass in mixing and in order to accomplish this, the particles must be mixed while the mass is under pressure. The drum 1 will resist outward pressure while the material is constantly moved 45 back and forth in the drum, the outer portion moving in one direction and the inner portion moving in the other direction and the two portions more or less mixed by reason of 50 the shape of the two vanes. The compressor 16 will prevent any vacant space while the mixing is going on. The concrete is mixed under pressure whereby the mortar portion 55 is uninfluenced by gravity and is forced among and upon the surfaces of the large aggregate of the mass.

The machine is to be provided with suitable gages or measuring devices for determining the amount of water and other elements and for determining the consistency of the mixture. The compressor 16 is provided with a scale so that the exact contents of the drum can be determined, as the 60 volume of the drum is known and the volume of the compressor is known.

In order to aid the mixing of the ingredients, provision may be made for vibrating the material by means of the vanes. The shaft 12 is provided with a bearing sleeve 22 which is rigid therewith. The sleeve 12 70 is journaled in the end of the drum 1 and the shaft 12 is placed slightly off the center of the sleeve 22. When the shaft is driven, the vanes 10 and 11 will be more or less vibrated. This will cause a more thorough mixing and the vanes will be turned more easily in the material by reason of the vibrations. It is apparent that other means 75 may be used to cause vibrations in the mass.

What I claim, is,—

1. A machine for mixing concrete and other plastic material comprising a drum in fixed position and provided with a closable inlet opening and a closable discharge opening, a screw-shaped vane mounted in 80 the drum, means for driving the vane and mechanical means for compressing the material being mixed so as to fill the voids therein and also to compact the binder material 85 on the coarse aggregate.

2. A machine for mixing concrete and other plastic material comprising a drum in fixed position and provided with an inlet opening and a discharge opening, means for closing and opening said openings, self-acting mechanical means for moving the outer portion of plastic material therein in one direction and the central portion of material in the opposite direction simultaneously and means for maintaining pressure 95 throughout the drum during operation for preventing any vacant spaces or air pockets therein.

3. A machine for mixing concrete and other plastic material under pressure comprising a drum in a fixed position and provided with closable inlet and discharge openings, means for moving the outer portion of material therein in one direction and the central portion of material in the opposite direction simultaneously, and means for applying pressure thereto throughout the whole mass simultaneously with the moving outer portion of material therein in one direction and the central portion of material in the opposite direction simultaneously.

4. A machine for mixing concrete and other plastic material under pressure comprising a drum in a fixed position and provided with closable inlet and discharge openings, a helical vane for moving a portion of the material in said drum in one direction and a helical vane for moving the other portion of the material in the opposite direction simultaneously, means for driving said vanes, and means for applying pressure to said material simultaneously with the moving thereof.

5. A machine for mixing concrete and other plastic material under pressure com-

- prising a drum in a fixed position and provided with closable inlet and discharge openings, an outer helical vane for moving the material in said drum in one direction and 5 an inner helical vane for moving the material in the opposite direction, means for driving said vanes, and a compressor for applying pressure to said material simultaneously with the moving thereof.
- 10 6. A machine for mixing concrete and other plastic material comprising a drum in a fixed position, a flat helical vane revolving in said drum, and independently movable means for applying pressure to the material in said drum.
- 15 7. In a drum fixed against movement and provided with closable and discharge openings, a flat helical vane revolving in said drum for moving the material in the central portion of said drum towards one end thereof and a flat helical vane revolving in said drum for moving the material in the outer portion of the material in the opposite direction simultaneously with the movement 20 in the central portion and solid mechanical means for applying pressure throughout the mass during a mixing operation.
- 25 8. A machine for mixing concrete and other plastic material comprising a drum fixed against movement, means for moving material in said drum in all parts thereof and a plunger for applying pressure to the entire mass of material during the moving thereof and for preventing any vacancy in 30 the drum.
- 35 9. A machine for mixing concrete and other plastic material comprising a drum fixed against movement, means for moving material throughout the interior thereof, and a movable compressor for applying pressure to the material during the moving thereof for forcing all air out of the material and for preventing any vacancy in said drum during a mixing operation.
- 40 45 10. A machine for mixing concrete and other plastic material comprising a drum fixed against movement, means for moving material throughout the interior thereof, a
- compressor for applying pressure to the material during the moving thereof and for preventing any vacancy in said drum during a mixing operation, and means for actuating said compressor.
11. A machine for mixing concrete and other plastic material comprising a drum fixed against movement, a revolving shaft projecting in said drum, a left hand helical vane and a right hand helical vane fixedly connected to said shaft for mixing and moving material back and forth in said drum and means for applying pressure throughout the mass for preventing any vacancy in said drum and for compacting the binding material on the coarse aggregate.
12. A machine for mixing concrete and other plastic material comprising a drum fixed against movement, a revolving shaft projecting in said drum, a right hand helical vane fixedly connected with said shaft and a left hand helical vane fixedly connected with said shaft and surrounding said right hand vane for moving material in said drum in opposite directions and mixing the material, and means for exerting pressure on said material simultaneously with the moving thereof.
13. A machine for mixing concrete and other plastic material comprising a drum in fixed position, a flat helical vane having means for revolving it in said drum for mixing material therein, and means connected off-center with said vane revolving means for causing vibrations in said vane.
14. A machine for mixing concrete and other plastic material comprising a drum in a fixed position, an outer left helical vane having means for revolving it in said drum and a right helical vane positioned within said outer vane and revolving simultaneously therewith, and means connected off center with said vane revolving means for causing vibrations in said vanes during operation.
- In testimony whereof, I set my hand this 16th day of January, 1923.
- ROBERT C. STUBBS.
